UNITED STATES PATENT OFFICE.

JOHN H. WHITE, OF ARKANSAS CITY, KANSAS.

HYDROCARBON-BURNER.

SPECIFICATION forming part of Letters Patent No. 599,577, dated February 22, 1898.

Application filed August 6, 1897. Serial No. 647,339. (No model.)

To all whom it may concern:

Be it known that I, JOHN H. WHITE, a citizen of the United States, residing at Arkansas City, in the county of Cowley and State of 5 Kansas, have invented a new and useful Hydrocarbon-Burner, of which the following is a specification.

My invention relates to hydrocarbon-burners, and particularly to that class wherein hydrocarbon oils are vaporized prior to ignition, the burner being combined with the vaporizing devices, whereby a compactly-constructed device is capable of performing the functions of a vaporizer and a mixer.

15 Further objects and advantages of this invention will appear in the following description, and the novel features thereof will be particularly pointed out in the appended claims.

20 In the drawings, Figure 1 is a diagrammatic view of a heating or lighting system embodying a burner constructed in accordance with my invention. Fig. 2 is a detail sectional view of the burner. Fig. 3 is a horizontal section of the same on the line 3 3 of Fig. 2. Fig. 25 4 is a plan view of the burner. Fig. 5 is a partial vertical section of the burner at right angles to the plane of Fig. 2.

Similar numerals of reference indicate corresponding parts in all the figures of the drawings.

1 designates a supply tank or reservoir communicating with a supply-pipe 2, fitted with a filling 3 of fibrous wicking, adapted to convey the fuel from the tank by capillary attraction, but especially designed to serve as a straining medium to remove impurities from the oil in its passage to the burners. Communicating with the supply-pipe is a series 35 of distributing-tubes 4 of smaller diameter, to which are attached the burners 5. In the construction illustrated in Fig. 1 the distributing-tubes are provided, respectively, with controlling-valves 6, while each branch pipe 40 7 is provided with an auxiliary controlling-valve 8, whereby either of the burners, located, respectively, at the outer extremities of the branch pipes 7, may be used independently of the other.

50 The burner proper consists of a vertical mixer-tube 9, enlarged at its upper end to form an exteriorly-cylindrical chamber 10, an in-

termediate flared portion being provided at 11 within the casting which forms the body portion of the burner. This body portion 12 55 is also cylindrical, and fitted thereon is the upper end of a cylindrical depending sleeve 13, which is thus arranged concentrically with the reduced or tubular portion 9 of the mixer. A feed-tube 14, preferably integral with the 60 body portion 12, is arranged within the shell (and hence within the contour of the body portion) parallel with the reduced portion of the mixer-tube and communicates through a bore in the body portion with a vaporizing-coil 15, 65 said coil being located centrally above the upper end of the enlarged portion or chamber of the mixer-tube and also above a reticulated or interstitial guard 16, which spans the open top of said chamber, while the arms at opposite sides of the coil, which are arranged within the circumference of the cylindrical chamber 10, communicate, respectively, with the feed-tube 14 and a burner-tube 17, which extends downwardly parallel with the mixer-tube 75 within the sleeve 5, and hence within the contour of the body portion 12, and terminates in a burner-orifice 18, controlled by a needle-valve 19.

The lower end of the sleeve or shell 13 is 80 open and the stem and guide of the needle-valve 19 project downwardly therethrough, said burner-orifice being arranged below the open lower end of the mixer-tube and spaced therefrom to provide for the influx of air or 85 other combustion-supporting agent.

The contents of the tank or reservoir should in operation be placed under fluid-pressure, (as air-pressure,) through a valved inlet 20, to force the fuel through the supply-pipe to 90 the distributing-tubes. The valve 6 is preferably of needle construction, and by it the supply of fuel to the burner, is regulated. Fuel passing through one of the branch pipes 7 enters the feed-tube of the burner, thence 95 passes through the vaporizing-coil, which is located above the guard at the top of the mixer-tube, and thence, in the form of vapor or gas, passes down the burner-tube and is discharged through the valve-controlled 100 burner-orifice into the lower end of the mixer-tube. With this construction it will be seen that the fuel in approaching the point of ignition must pass through a coil which is ar-

ranged in the path of the flame, and as said coil is made of tubing of small diameter the rapid and complete vaporization thereof is the result. The cylindrical sleeve or shell protects the feed-tube, burner-tube, and mixer-tube from drafts of air, and hence provides for the accurate discharge of the vaporized fuel from the burner-orifice into the lower end of the mixer-tube and also prevents the conveying members of the burner from being chilled. This sleeve or shell is preferably removable from the collar of the mixer-tube to give access to the interior of the burner.

It will be understood that in practice the tank or reservoir may be arranged either underground or above the plane of the burners, as may be found most convenient.

It will be seen from the foregoing description that the burner embodying my invention is adapted for producing a non-luminous flame, but as the particular construction set forth is adapted for illuminating purposes it will be understood that the desired result can be produced by employing in connection therewith a refractory mantle, (not shown,) which may be constructed as in the ordinary practice and is designed to perform the function well known in the art. Hence the advantage in constructing the burner with an enlarged body portion from which depends a protective shield inclosing the feed and burner tubes, while the upwardly-extending cylindrical chamber 10 is of less diameter than the body portion to form a shoulder at the upper end of the latter suitable to support a refractory mantle of the ordinary construction. Furthermore, an additional advantage of the construction described resides in the fact that the vaporizing-tube, which is employed in connection with the feed and burner tubes and includes a coil located above the said cylindrical chamber and interstitial guard, has its arms or terminal portions, as well as said coil, arranged wholly within the circumferential contour of the chamber 10, so as not to interfere with the application of a suitable refractory mantle, if the use of such should be desired.

The burner, as described, is compact in construction and is particularly adapted for illuminating purposes, as will be shown by the bracket branches disclosed in Fig. 1, and the enlarged supply-pipe, through which extends the continuous straining and conveying wicking, is designed to deposit liquid fuel, with the desired rapidity of flow, into the branch pipe, which obviously is of less diameter and hence less capacity.

Various changes in the form, proportion, and the minor details of construction may be

resorted to without departing from the spirit or sacrificing any of the advantages of this invention.

Having described my invention, what I claim is—

1. A burner having a cylindrical body portion and a depending open-bottomed sleeve of equal diameter therewith, a mixer-tube depending centrally from the body portion within said sleeve and having an open lower end, feed and burner tubes located within the sleeve below the body portion, the burner-tube terminating in a valve-controlled burner-orifice axially aligned with the mixer-tube, a cylindrical chamber rising from the body portion and of less diameter than the same, to form an enlarged cavity in communication with the mixer-tube, and provided at its top with an interstitial guard, and a vaporizing-tube arranged above and within the circumferential contour of said cylindrical chamber, with its arms arranged within the chamber and in communication with said feed and burner tubes, respectively, to convey fuel from the former to the latter, substantially as specified.

2. A burner having a mixer-tube provided with a reduced lower portion depending from an enlarged cylindrical portion and terminating at its top in an exteriorly-cylindrical chamber, of smaller diameter than the body portion and fitted with an interstitial guard, a feed-tube and a burner-tube arranged parallel with and contiguous to the reduced portion of the mixer-tube and beneath and within the circumferential contour of the body portion, said burner-tube terminating in a valve-controlled burner-orifice aligned with the center of the mixer-tube and located below the open lower end thereof, a vaporizing-coil located above the interstitial guard and connecting the feed-tube with the burner-tube, and having its arms located within the circumferential contour of said chamber of the mixer-tube and a cylindrical shell or sleeve fitted upon the enlargement of the mixer-tube at its upper end, inclosing the reduced portion of the mixer-tube and the feed and burner tubes, and having an open lower end through which the burner-orifice controlling-valve is accessible, substantially as specified.

In testimony that I claim the foregoing as my own I have hereto affixed my signature in the presence of two witnesses.

JOHN H. WHITE.
